BY *WILLIAM E. RENO*
A. B. Bowman
ATTORNEY

UNITED STATES PATENT OFFICE

WILLIAM E. RENO, OF GLENDALE, CALIFORNIA

HEATER

Application filed April 15, 1930. Serial No. 444,428.

My invention relates to heaters, and particularly to heaters for heating buildings or rooms of buildings.

The objects of this invention are: first, to provide a furnace or heater of this class for indirectly heating air for the rooms of buildings, and one which is simple and economical of construction and economical to operate; second, to provide a furnace or heater of this class having therein curved air ducts or flues which are exteriorly heated, the curved ducts or flues providing resistance to the free passage of air or gas therethrough so that the air or gas is much more efficiently heated than in structures where the air or gas passes through straight flues or ducts, the exterior surfaces of the flues providing also more efficient impinging thereagainst of the heating gases of combustion; third, to provide novel arrangement and spacing of ogee curved flues in which the passages through the flues are uniform but the passages between the flues, in the direction of the curves from front to rear, that is, of the flues, are constricted so as to confine the flow of heating gases of combustion, passing between the flues and from one lateral side of the heater to the other, at or adjacent the ends or open portions of the flues, but still permitting passage of the heating gases over the whole upper and lower exterior surfaces of the flues and from the rear side of the enclosing casing to the front side; fourth, to provide a furnace or heater of this class having uniform ogee curved flues, and such flues in which the opposite sides or curved walls thereof are identical but positioned in reverse order from each other, such uniformity of parts providing for very economical construction; fifth, to provide a furnace or heater of this class having upwardly directed and curved flues extending from the rear wall to the front wall and having the hot gases of combustion so directed as to distribute the hot gases very uniformly over the exterior surfaces of the flues; sixth, to provide a novel method of securing the opposite sides of the flues together and of mounting the same in a casing; seventh, to provide a furnace or heater of this class in which the features above mentioned

are embodied in a wall heater and in which the air from the room is directed backwardly at the lower portion of the heating casing to the rear portion thereof, thence through the heating flues back into the room; eighth, to provide as a whole a novelly constructed furnace or heater of the class mentioned; and, ninth, to provide a furnace or heater of this class which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawing and to the characters of reference thereon which form a part of this application in which:

Figure 1 is a partial front elevational and partial sectional view of my heater in one form of construction and embodied in a wall heater for rooms, the view being taken at 1—1 of Fig. 2; Fig. 2 is a sectional view thereof taken at 2—2 of Fig. 1; Fig. 3 is a sectional view thereof taken at 3—3 of Fig. 1; Fig. 4 is an enlarged fragmentary perspective view showing one method of mounting the curved plate of the flues within the casing and of securing the same together; and, Fig. 5 is a fragmentary sectional view of my heater in a slightly modified form of construction, showing the lateral arrangement of the flues and passages.

Like characters of reference refer to similar parts and portions throughout the views of the drawing.

My heater, as illustrated in the drawing, is enclosed in a metal casing 1 which may be either sheet or cast metal. This casing is provided with a rear wall 1a and a second rear wall 1b spaced inwardly from the former, and is also provided with a front wall 1c. This casing is also provided with a double bottom consisting of a lower bottom wall 1d and an upper bottom wall 1e. The space between the walls 1d and 1e forms a passage connecting the interior of the room in which the heater is located with the passage formed

between the walls $1a$ and $1b$. It will be noted, however, that the passage between the walls $1d$ and $1e$ may be connected to any other source of air to be heated.

- 5 Within the casing are positioned in superimposed relation a plurality of flues 2 . These flues are positioned between and supported by the rear wall $1b$ and the front wall $1c$ and extend in an upwardly and curved direction
 10 from the former to the latter connecting the rear passage with the room. The flues extend between and are preferably secured at their lateral sides to the side walls $1f$ and $1g$. The flues are curved in ogee form from the
 15 rear wall $1b$ to the front wall $1c$ and may be of uniform thickness from the rear opening to the front opening of the flues. The upper and lower plates of the flues are of identical construction, but are positioned in reverse
 20 order from each other, the rear portion of the upper wall of each flue being of the same curvature as the front portion of the lower wall thereof and the front portion of the upper wall being of the same curvature as the
 25 rear portion of the lower wall. The walls are so shaped that all of them may be made from one die and so that they may be nested one within the other. All of the flues are of the same shape, but when superimposed one
 30 over the other within the casing, the space between adjacent flues, and intermediate the rear and front openings thereof, is constricted, as shown in Fig. 2, preventing free flow of hot gases of combustion from the space at
 35 the rear portion of the heater and between adjacent flues, toward the front space between the flues, as shown in Fig. 2. These spaces between adjacent flues, and near the ends of the ogee curves, form longitudinal
 40 passages A and B at the rear and front portions of the casing. These passages are connected at the alternate ends of the flues by means of rectangular cut out portions $2a$ and
 45 $2b$ at the ends and corners of the flues, as shown best in Figs. 1, 2 and 3, the longitudinal passages A at the rear of the heater forming with the vertical connecting passages or openings $2a$, a zigzag passage for the gases of combustion from the lower portion of the heater to the upper portion. The passages B form with the vertical passages or openings $2b$ similar zigzag passages. Although these
 50 passages at the rear and forward portion of the heater are substantially separate, the slight space between the flues at the middle portion of the heater permits the gases of combustion from the rear passages A to flow upwardly toward the front passages B so as
 55 to permit the impinging of hot gases of combustion over substantially the whole of the interior surfaces of the flues.

The flues may be made of sheet metal plates $2c$ secured together at their ends by
 60 end members $2d$ which are cast with the edges

of the plates $2c$ cast in place. In the end members $2d$ may be arranged the vertical openings or passages $2a$ and $2b$, as shown in Fig. 4.

In the furnace or heater shown in the drawing, the heat is provided by a burner 3 which is positioned at the lower portion and preferably near the front side thereof. The burner, in this instance, is shown mounted on the wall or upper bottom $1e$ and receives its supply of oxygen from the passage between the bottom walls $1d$ and $1e$. The flame of the burner is directed backwardly so that the greater portion of the gases of combustion pass upwardly through the rear vertical passages $2a$. There is provided in the casing below the lowermost flue 2 a baffle plate 4 which facilitates the directing of the flame backwardly. At the upper end of the casing is a stack or duct 5 which communicates with the compartment above the uppermost flue and is adapted to direct the spent gases of combustion upwardly.

In the modified construction shown in Fig. 5, there is a similar arrangement of flues, but in this instance the lateral sides or ends of the flues 2 terminate short of the side walls $1f$ and $1g$ leaving vertical spaces between said ends and the side walls of the casing. These spaces or vertical passages are separated by spacers 6 which secure the flues to the side walls and also divide the spaces at ends or sides so that the gases of combustion cannot flow directly into the stack, but serve as baffles for directing the gases of combustion from one horizontal passage B to another around the lateral side or end of each of the flues. The spacers or baffles 6 are of substantially the curvature of the flues. Thus, in this instance, the whole of the end or lateral side of the casing at the lateral sides of the flues are connected instead of merely through small vertical passages.

At the front side of the casing is a perforated grating 7 having perforations for admitting hot air from the flues into the room. At the lower end of the grating are also perforations for admitting air from the room into the space between the bottom walls $1d$ and $1e$.

Though I have shown and described a particular construction, combination and arrangement of parts and portions, and a certain modification thereof, I do not wish to be limited to this particular construction, combination and arrangement, nor to the modification, but desire to include in the scope of my invention the construction, combination and arrangement substantially as set forth in the appended claims.

Having thus described my invention, what I desire to secure by Letters Patent is:

1. In a heater of the class described, a casing having a plurality of separate superimposed air conducting flues extending from the

back to the front side of the casing, said flues being flat laterally and curved and directed upwardly from the back to the front side of the casing, and a burner below the lowermost 5 flue, said casing having vertical passages at the lateral ends of the flues for connecting the spaces below alternate flues to the next upper spaces forming a zigzag passage for gases of combustion between and around the 10 ends of the flues.

2. In a heater of the class described, a casing having a plurality of separate air conducting flues extending from the back to the front side of the casing, each of said flues 15 being flat laterally and curved and directed upwardly from the back to the front side of the casing adapted to receive air at the lower rear ends and discharge air at the front ends of the flues, and means for heating the upper 20 and lower sides of the flues.

3. In a heater of the class described, a casing having separate superimposed air conducting flues extending from the back to the front side of the casing, said flues being flat 25 laterally and curved and directed upwardly from the back to the front side of the casing, and a burner below the lowermost flue, the lateral sides of the flues having cut out portions at the rear and front sides of the flues 30 forming upwardly directed passages for the gases of combustion from said burner, said passages connecting the spaces at the lower and upper sides at alternate ends of adjacent flues.

4. In a heater of the class described, a casing, separate flues positioned in superimposed relation in the casing and extending from one side thereof to the other, each of the flues 35 being open at the portions adjacent said sides of the casing; and directed upwardly from the former to the latter side, said flues being of substantially uniform thickness and in general ogee form in longitudinal cross section, and a burner positioned below the lowermost 40 flue, the alternate ends of adjacent flues being provided at the ends of the ogee portions of the flues with cut out portions forming upwardly directed passages for directing the gases of combustion from the 45 burner through the casing from one side of the casing to the other in zigzag form.

5. In a heater of the class described, a casing, separate flues positioned in superimposed relation in the casing and extending from one side thereof to the other, each of the flues 55 being open at the portions adjacent said sides of the casing; and directed upwardly from the former to the latter side, said flues being of substantially uniform thickness and in general ogee form in longitudinal cross section, and a burner positioned below the lowermost 60 flue, the alternate ends of adjacent flues being provided at the ends of the ogee portions of the flues with cut out portions forming upwardly directed passages for directing the 65

gases of combustion from the burner through the casing from one side of the casing to the other in zigzag form, the spaces between adjacent flues being constricted intermediate the ends of the ogee curves of the flues. 70

6. In a heater of the class described, a casing having its rear side connected with a source of air, a plurality of superimposed air conducting flues mounted within the casing and directed upwardly from the rear side to the front side of the casing, the cross section of said flues from rear to front being in general ogee form, heating means at the lower portion of the casing below the lowermost flue, there being provided in the casing at the alternate lateral sides of the flues passages connecting the spaces at the lower and upper sides of said flues at said ends, forming a zigzag passage through the furnace between the flues for the passage of gases of combustion from the burner therethrough, and a baffle positioned in the lower portion of the casing above the burner for directing the hot gases of combustion from the burner backwardly to the lower side and rear portion of the lowermost flue. 80

7. In a heater of the class described, a casing, and a multiplicity of air conducting flues positioned in superimposed relation and extending in an upward direction from one side of the casing to the other, said flues being of substantially uniform thickness from one side of the casing to the other, the longitudinal cross section of said flues being in ogee curved form, the lower and upper walls of each flue being of identical curvature and shape, but secured in spaced relation to each other in reverse order. 90

8. In a heater of the class described, a casing, a multiplicity of air conducting flues positioned in superimposed relation and extending in an upward direction from one side of the casing to the other, said flues being of substantially uniform thickness from one side of the casing to the other, the longitudinal cross section of said flues being in ogee curved form, the lower and upper walls of each flue being of identical curvature and shape, but secured in spaced relation to each other in reverse order, and a burner means within the casing below the lowermost flue, there being provided in the casing passages at the alternate ends of adjacent flues forming a zigzag passage through the burner for the passage of the gases of combustion from the burner therethrough, said passages at the ends of the flues being relatively narrow and positioned at the end portions of the ogee curves of the flues, the spaces between adjacent flues and between the ends of the ogee curves thereof being constricted, substantially confining the gases of combustion through the casing to the spaces adjacent the ends of the ogee curves. 110

9. In a heater of the class described, a 120

casing, a plurality of wide relatively flat flues positioned with their flat sides adjacent and in closely spaced relation relative to each other therein and terminating at their open ends at spaced walls therein, said flues being curved between said walls forming resistance to the passage of gases therethrough and causing said gases to impinge against the opposite walls of the flues, and means for

10 heating the outer sides of the flues.

10. In a heater of the class described, a casing having spaced walls at its rear portion, and a passage connecting the lower portion of the front side of the casing with the space 15 between said walls, said casing having also a front wall, a plurality of relatively flat curved air ducts positioned with their flat sides adjacent each other extending in an upward direction from the inner of the rear walls to the 20 front wall and connecting the space between the two rear walls with the front of the casing, means within the casing for heating the outer walls of the ducts, and a perforate grating positioned over the front side of the 25 casing, over the front wall and the open front end of the ducts.

11. In a heater of the class described, a casing, and a wide flue extending substantially 30 between the lateral sides of the casing and curved from the rear to the front portions thereof and extending with said rear and front portions through the rear and front walls of the casing.

12. In a heater of the class described, a casing having a plurality of separate superimposed air conducting flues extending from one 35 side of the casing to the other, said flues being flat laterally and curved upwardly from said one side of the casing to the other for receiving air at the lower portion of the flue and discharging air at the upper end of the flue, and means for heating the flues.

13. In a heater of the class described, a casing having a plurality of separate superimposed flat flues extending from one side 45 thereof to the other, each of the flues being open at the portions adjacent said sides of the casing, said flues being flat laterally and in general ogee form between said sides of the 50 casing.

14. In a heater of the class described, a casing having a plurality of separate superimposed flat flues extending from one side thereof to the other, each of the flues being open at the portions adjacent said sides of the casing, said flues being flat between the lateral sides of the casing and in general ogee form from the rear to the front side of the casing, the ends of said flues being substantially normal with the rear and the front sides of the casing.

In testimony whereof, I have hereunto set my hand at Los Angeles, California this 8th day of April, 1930.
